MAX W. FEDERBUSH AND JAY D. FEDERBUSH, OF NEW YORK, N. Y.

AUTOMATIC LOCKING DEVICE FOR LOOSE LEAF BINDERS

Application filed December 5, 1930. Serial No. 500,170.

This invention relates to loose leaf binders, and has particular reference to locking devices therefor.

One object of the invention is to provide a loose leaf binder having improved means including pivoted jaws for locking engagement with the binder posts.

Another object of the invention is the provision of a loose leaf binder having an improved device for automatically locking the binder closed at the posts thereof; said device being releasable by means including a finger piece movable transversely of the plane of the binder for rapidly and easily opening the binder.

Another object of the invention is to furnish an improved locking device for a loose leaf binder including an actuating bar and finger piece therefor mounting the bar.

Another object of the invention is to provide a loose leaf binder having posts and locking jaws therefor together with an actuating bar in improved relation for moving the jaws laterally of the posts into released position; and especially to combine this coaction with a pivotal movement of the jaws.

Another object is to construct a loose leaf binder having an automatic spring actuated locking device including swingably mounted locking jaws for engaging the binder post and a single bar for actuating both jaws arranged in improved co-ordination.

Other objects of the invention are to provide a locking device having jaws carried by actuating springs, which springs may pivotally mount the jaws.

A further object is to provide an improved automatic locking device for a loose leaf binder, having comparatively few and simple parts, and which is inexpensive to manufacture and assemble, and durable, reliable, and efficient in use, and which may be conveniently and rapidly operated.

This invention is especially intended for holding sheets of paper having conventional slotted holes for receiving the loose leaf binder posts, and from which the sheets may be readily withdrawn upon slightly loosening or opening the binder, but without the necessity of entirely separating the covers thereof.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters throughout the several views.

In the drawings:

Figure 1 is a plan view of a loose leaf binder embodying the invention.

Fig. 2 is an enlarged plan view of the back portion of the binder detached from the covers, and with parts removed to show the internal construction.

Fig. 3 is a longitudinal sectional view taken on line 3—3 of Fig. 2.

Fig. 4 is an enlarged transverse sectional view taken on line 4—4 of Fig. 2.

Fig. 5 is a fragmentary longitudinal sectional view of a portion of the locking device, including a spring actuated pivoted jaw in locking position.

Fig. 6 is a fragmentary longitudinal sectional view showing a portion of the locking device in released position.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawings, therefore, are submitted merely as showing the preferred exemplification of the invention.

Referring in detail to the drawings, 10 denotes a loose leaf binder embodying the invention. The same may include a plurality of covers 11, each of which is pivotally mounted at 12 in a pair of angle arms or brackets 13 rigidly secured to the ends of a back 14 of the binder. Said back includes a plurality of separate portions 15, 16, one for

each cover, which may be in the nature of flattened longitudinally split sheet metal tubes and coextensive in size and similar in shape with each other. In the tube 16 are 5 secured a plurality of anchor elements such as nuts 17 with which are engaged the posts 18. The latter extend perpendicularly and may be of sectional construction so that said posts may be lengthened whereby the binder 10 may receive any desired amount of stock. Formed in the walls of the tube 15 are a plurality of aligned holes 19, 20 in the walls 15a and 15b for receiving the posts, and disposed in the same tube is an automatic device for 15 releasable locking engagement with the said posts. Obviously the tubes 15 and 16 may be neatly finished or covered as may be desired. As thus arranged, the locking device may be released so that the back portions 15, 16, and 20 hence the covers 11 may be separated, and the loose leaf sheet filler inserted upon the posts. Then the back portion 15 and its cover are placed so that the posts 18 are passed through the holes 19, 20 and locked by the automatic 25 device. When a sheet of paper is to be removed, it suffices to release the locking device and loosen the binder, whereby the sheet may be withdrawn by virtue of the slotted holes therein provided, and which being conventional, have not been shown. The loose leaf binder above described is a standard construction, and is submitted in an illustrative and not in a limiting sense, and the automatic locking device which constitutes our 30 invention will now be described.

Coacting with each post 18 is a movable or pivoted locking jaw 21 which is adapted to frictionally grip the post. The said jaw may assume various shapes and constructions, and yet move between post gripping and releasing positions. While said jaw may move in different ways for this purpose, the pivoted arrangement has the advantage of simplicity, besides being easily actuatable. 40 Thus the jaw may assume the form of an angle member, being provided with a portion 22. The latter may have a plurality of spaced points 23 extending pivotally into corresponding holes 24 in the wall 15a of the member 15. Said holes 24 may be sufficiently large to constitute guide openings permitting a certain degree of movement of the points 23 therein, so that the member 22 may slightly slide on the wall 15a as the pivotal 45 movement of the jaw occurs in part on a spring hereinafter described. The portion of the member 22 intermediate of the said points may have pivotal abutment relation at 50 with the wall 15a of the member 15 as shown in Fig. 4. The jaw 21 may engage a post 18, for example, by receiving the latter in a hole 26 which is substantially aligned with the holes 19, 20. This hole may have sufficient clearance with the post to permit the 55 jaw to swing into the engaging position. To

tend to throw the jaw automatically into locking position, a resilient means may be associated with some portion of the locking device, and may generally be considered as an element of the actuating means for the jaw. Preferably said resilient means may directly 70 act upon and carry the jaw, and may be embodied in a spring such as 27.

The spring 27 may consist of a single piece of wire including a pair of spaced coil portions 28 interconnected by a U including the longitudinal portions 29 and a transverse portion 30 joining the same together. Also extending from the coils are the spring portions 31, which pass through undercuts 31a in the member 22, and which are offset at 32 to engage in holes 33 of the jaw, with the free ends 34 bearing upon the jaw. Since the U portion of the spring bears upon wall 15b of the casing 15 the jaw is not only swung toward the opposite wall 15a, but the pivot points 23 are thereby retained in floating or sliding and pivotal engagement in the holes 24. When thus actuated by the spring, the jaw frictionally grips or bites into the post 80 85 90 95 100 105 110 115 120 125 130 135 140 145 150 155 160 165 170 175 180 185 190 195 200 205 210 215 220 225 sition on the edge 41 of the step when the jaws are returned to locking position.

By making the bar 38 out of a pair of strips of metal, the stepped structure may be easily constructed.

5 A simple and yet reliable mounting for the bar 38 may be obtained by rigidly securing the same to the shank 43 of the finger piece 37. Said shank is slidable in a hole 44 in the wall 15b, and with the finger piece head forming a suitable mounting for said bar, which is moreover retained by the tubular member 15. As the bar 38 acts in opposite directions upon the locking jaws, the reaction 10 on said bar is such as to produce an equal resistance of the springs 27. When the leaf device is locked, the finger piece is in a position closely adjacent to the wall 15b, but when the device is to be opened, a pull is exerted on the finger piece to actuate the bar 20 38, release the locking jaws and at the same time to open the binder to the desired degree.

It will be obvious that the principles of this invention may be embodied in locking devices 25 for many different purposes other than for loose leaf binders as the invention may be broadly considered as including any type of bolt and the improved actuating and engaging means therefor, while the post is representative of an engaging part.

30 It will be appreciated that various changes and modifications may be made in the device as shown in the drawings, and that the same is submitted in an illustrative and not in a limiting sense, the scope of the invention being defined in the following claims.

We claim:

1. A loose leaf binder having a post, a jaw 40 swingably mounted on one side of the post for engaging the post, and actuating means for the jaw on the opposite side of the post, said actuating means having one end portion for swinging the jaw, and another end portion to retain the jaw in swung position independently of the first portion.

45 2. In a loose leaf binder having a post and a casing, the combination of a jaw swingably mounted on a wall of the casing, and resilient means pressing the jaw into engagement with 50 said wall and tending to swing the jaw into transverse engagement with the post, and actuating means to release the jaw movable in the direction of said post, said jaw including a beveled portion engageable by the actuating 55 means for swinging the same.

3. A loose leaf binder having a pair of spaced posts, jaws swingably mounted and having portions extending toward each other for engaging the posts, and means for 60 swinging the jaws, said means including means for moving apart said portions of the jaws coincident with the swinging action.

65 4. In a loose leaf binder having a post, the combination of a jaw pivotally movable with

respect to the post for gripping the same, said jaw having a beveled end portion, actuating means having a stepped portion for moving the beveled portion to release the jaw, said beveled portion bearing on an upper edge of 70 the stepped portion in the locked position of the jaw, said beveled portion sliding downward into engagement with a flat portion of the step in the released position of the bolt, and other means for moving the jaw into the 75 locking position.

In testimony whereof we affix our signatures.

MAX W. FEDERBUSH.
JAY D. FEDERBUSH.
